UNITED STATES PATENT OFFICE

96,951

DESIGN FOR AN ENVELOPE OR SIMILAR CONTAINER

Edward Zupnik, Washington, D. C.

Application February 25, 1935, Serial No. 55,618

Term of patent 3½ years

To all whom it may concern:

Be it known that I, Edward Zupnik, a citizen of the United States, residing at Washington, in the District of Columbia, have invented a new, original, and ornamental Design for an Envelope or Similar Container, of which the following is a specification, reference being had to the accompanying drawing, forming part thereof.

I claim:

The ornamental design for an envelope or similar container substantially as shown.

EDWARD ZUPNIK.
